(57) **CLAIM**

The ornamental design for a curved wheel leveler, as shown and described.

DESCRIPTION

FIG. 1 is a top, front, right side perspective view of a curved wheel leveler showing our new design;

FIG. 2 is a front elevational view thereof;

FIG. 3 is a rear elevational view thereof

FIG. 4 is a top plan view thereof;

FIG. 5 is a bottom plan view thereof;

FIG. 6 is a left side elevational view thereof, the right side elevational view being a mirror image thereof;

FIG. 7 bottom, front, right side perspective view thereof;

FIG. 8 is a top, front, right side perspective view of a second embodiment of a curved wheel leveler, the dashed lines represent environmental structure only and form no part of the claimed design;

FIG. 9 is a front elevational view thereof, the dashed lines represent environmental structure only and form no part of the claimed design;

FIG. 10 is a rear elevational view thereof, the dashed lines represent environmental structure only and form no part of the claimed design;

FIG. 11 is a top plan view thereof, the dashed lines represent environmental structure only and form no part of the claimed design;

FIG. 12 is a bottom plan view thereof, the dashed lines represent environmental structure only and form no part of the claimed design;

FIG. 13 is a left side elevational view thereof, the right side elevational view being a mirror image thereof; and,

FIG. 14 bottom, front, right side perspective view thereof, the dashed lines represent environmental structure only and form no part of the claimed design.
